corporation of Delaware

Application December 15, 1949, Serial No. 133,053

23 Claims. (Cl. 197—63)

1

This invention relates to typewriting machines and related machines, and more particularly to mechanisms for adjusting carriage arresting stops, such as margin stops, to desired positions by remote control through manipulations involving stop-shifting movement of the carriage, without the operator ever laying hands directly on such stops.

Stop setting mechanisms of this general type have been devised advantageously for typewriting machines which have the stops adjustably supported behind the paper supporting devices, and wherein the stops thus are inconvenient for direct access.

Setting or adjusting mechanisms of the stated general type have in recent years been widely developed for adjustment of margin defining stops.

According to one known species of the stated general type of margin stop adjusting structures, a margin stop to be adjusted, as an initial step in the adjusting procedure therefor, is required to be brought into margin-limiting engagement with a counterstop, this being accomplished in a usual manner, for example by operation of the conventional carriage release lever, followed by movement of the carriage. Subsequently to this, the operator is required to operate a special manipulative control to unlock the margin stop for adjustment along its support and to render the unlocked stop temporarily stationary with respect to the counterstop. Thereupon with this condition maintained, the carriage is moved to the position where the stop is desired to be active in the future, the adjustment of the margin stop on its support to the new margin defining position being resultant. To secure the thus adjusted stop in the new stopping position on its support and to render it movable again with respect to the counterstop, the operator finally restores the stated special manipulative control.

According to the known structure to which reference has been made in the preceding paragraph, an operator must be ever conscious and careful to bring the margin stop in its old adjusted or set position into abutting relationship with the counterstop before the special manipulative control is operated. Should an operator fail to follow this prescribed procedure, the device will either not function at all, or it will function imperfectly, meaning of course, that for practical and useful action it must be operated in accordance with the hereinabove outlined rigid procedure. Should the operator fail to follow the prescribed procedure, control over the stop

to be adjusted is liable to be lost temporarily, and the operator is not only apt to become confused, but must make a fresh start.

According to the present invention, a margin stop is releasable from its support by operating force applied on a remote control, and release of the stop occurs immediately in case an abutting relationship has previously been established between the stop and counterstop. However, if the stated relationship is yet to be established, operating pressure exerted on said control will have resultful effect automatically when the required abutting relationship of the margin stop and counterstop is brought about by carriage movement. In any event, operating force on said control, if the required relationship of the stop and counterstop is established, renders the stop stationary with respect to the counterstop and substantially at the same time unlocks the stop from its support. When operating pressure on said control takes effect to render the stop stationary with respect to the counterstop, the said control has the further effect to release or maintain released the letter-feed mechanism. Consequently the stop is always under perfect control, either locked to its support in adjusted position, or held in fixed relationship with the counterstop for facilitating adjustment by carriage movement.

In view of the foregoing, it is an important object of the invention to provide a stop adjusting device of the stated general species which lends itself to more carefree and efficient manipulation by the operator.

It is particularly also an object of the invention to provide efficient, reliably operative means whereby in a stop adjusting feature of the stated species, an unlocking operation of a stop by a remote control must follow or is delayed to follow under any circumstances the bringing of the stop by carriage movement into abutting relation with the counterstop.

It is also an object of the invention to provide stop unlocking means including a control therefore of such structure that when operating pressure is exerted on said control there will follow a resultful effect to release a stop for adjustment only in the event such stop previously has been given an abutting relationship with the counterstop, or following establishment of such abutting relationship by carriage movement while operating pressure is applied on said control, but in no other event.

An object ancillary to the last one is to provide means whereby the margin stop is rendered sta-

tionary with respect to the counterstop consequential to the stated resultful effect, and whereby as an adjunct phase to said resultful effect the carriage will be free for movement to adjust the unlocked margin stop.

It is furthermore an object of the invention to provide an easily and conveniently manipulative margin stop adjusting structure wherein stop adjustment results from carriage movement, and not by unreliable spring power as has been employed in some prior devices.

It is another object of the invention to provide a margin stop adjusting device of the stated species having efficient provision to suppress operativeness of a manipulative control for stop unlocking action, until such time or unless a margin stop to be adjusted is first brought into abutting relationship with the counterstop.

Other objects and features will be in part obvious and in part pointed out particularly as the following description of a preferred embodiment of the invention proceeds.

Referring now to the drawings:

Figure 1 is a left hand sectional side view of a portion of a typewriter, mainly consisting of the carriage, and embodying the mechanism of the invention in normal position.

Figure 2 is a fragmentary rear perspective view of a carriage-supported stop unlocking control and mechanism controlled thereby, all parts being shown in normal position.

Figure 3 is a sectional front elevation illustrating some carriage-supported parts of the margin stop adjusting feature and also some frame-supported parts, the carriage being in position ready for release of such stop.

Figure 4 is a rear perspective view of some of the parts of the invention, all in their normal positions.

Figure 5 is a sectional side elevation of the carriage looking rightwardly at the right carriage end, and illustrating the support of certain movable parts.

Figure 6 is a fractional front view, illustrating the line-end margin stop as having been unlocked for adjustment by carriage movement.

Figure 7 shows substantially the same parts as are shown in Figure 6, and in the same state of operation, but as viewed from the top.

Figure 8 shows in enlarged aspect, as viewed from the front, a margin stop, together with a portion of a releaser therefor, the latter being in normal, ineffective position.

Finally, Figure 9 is a view similar to Figure 8, but the margin stop is shown as having been unlocked by the releaser for adjustment.

Referring now more particularly to Figure 1, a paper-supporting carriage, generally designated by the reference numeral 10, includes a rail-bar 11 which by means of anti-friction elements 12 is guided to travel on a stationary, frame-supported trackway 13. The carriage includes upright end plates 14, unitarily rising up from the opposite ends of the rail-bar 11. A usual platen indicated by dot-and-dash lines at 15 is carried turnably on said carriage ends 14. The types of the machine, as indicated at 16, are adapted to strike against the front side of the platen in a usual manner. A carriage feed rack 17 of conventional structure is carried on two spaced supporting arms 20 which are pivoted on the carriage as at 21. The rack 17 is normally in mesh with a gear pinion 22 which is carried fast on a vertical shaft 23, the latter being rotatably supported in the frame-work of the machine, and being controlled by a usual escape-

ment, not shown, to rotate in the required direction stepwise in response to typing and word spacing operations to letter-feed the carriage. A conventional spring motor, not shown, urges the carriage 10 constantly in letter-feed direction, leftwardly as seen from the front of the machine, the stated escapement exerting control so that in response to each typing operation there ensues a letter-feed movement of the carriage. The escapement, in a usual manner, permits movement of the carriage in return direction, and at the conclusion of such movement will hold the carriage in a letter-feed position.

To place the carriage speedily in any desired position, there is provided on each carriage end a usual carriage release lever or key 24 which when displaced toward the front of the machine will cause an upward displacement of the carriage feed rack 17 free of the pinion 22. Said carriage release levers 24 are pivoted as indicated at 25 upon the ends 14 of the carriage, and each has a link connection 26 with one of the arms 20 that support the feed rack 17. A spring 27, connected to and pulling forwardly on the link 26, maintains the feed rack 17 normally in the lower position seen in Figure 1, in mesh with the pinion 22, wherefore the carriage is normally held in any letter-feed position under control of the escapement.

The carriage 10 has extending parallel to the platen, to the rear thereof, see Figure 3, a bar 32 which supports or carries adjustably therealong a left margin stop 33 and a right margin stop 34. The bar 32, see also Figure 7, is fastened at opposite ends by bolts 35 to the opposite carriage ends 14. The said bar 32 has notches 36 along the lower edge thereof at intervals corresponding to the letter-feed spaces, and each of the stops 33 and 34 is equipped with a device generally designated by the numeral 37 which normally in cooperation with the notches 36 of the bar 32 serves to lock or detent the stated stops 33, 34 individually in margin defining positions. Referring specifically to Figures 3, 4 and 8, each detent device 37 comprises a pintle 38 having a transverse cut 40 therein and carrying fixedly at the rear an arm 41. Each pintle 38 is accommodated pivotally in a transverse perforation of its margin stop. Said transverse cut 40 forms on the pintle a detenting tooth at 42 for margin stop holding engagement with any one of the notches 36 of the rack bar 32. A torsion spring 43 accommodated upon each pintle 38 between the margin stop and the arm 41 is arranged to urge the latter resiliently for the pintle in the margin stop to turn appropriately to cause the detenting tooth 42 to bite into whichever one of the rack notches 36 is opposite thereto. The pintle 38 is circular in front of the transverse cut, and thus a shoulder is provided along the front edge of the transverse cut 40 which when the stop is assembled on the rack serves to retain the pintle on the stop by cooperation with the front face of the rack bar 32. The transverse cut 40 in the pintle 38 of the left hand margin stop 33 is appropriately provided so that, as viewed from the front of the machine, the detent tooth 42 formed thereby enters into the rack notch by clockwise rotation of the pintle, the spring 43 for such stop being appropriately arranged to urge the pintle clockwise. Conversely, the transverse cut 40 in the pintle 38 of the right hand margin stop 33 is appropriately provided for the detent tooth 42 to enter the rack notch by anti-clockwise rotation of the

pintle, the spring 43 being appropriately arranged to urge the pintle anti-clockwise.

The stated margin stops 33, 34 cooperate with a usual frame-carried counterstop 46, see Figures 1 and 4, for left and right margin gaging function. Said counterstop 46, see Figure 1, is in the form of an upright arm which at its lower end pivots on a stationary stud 47 and which protrudes upwardly through a substantially rectangular clearance 48 in a top plate 50 of a housing 51, the latter constituting part of the rigid framework of the machine. The counterstop 46 has capacity for limited lateral motion in the clearance 48, a spring 52 being associated with the counterstop to cause the same normally to lean against the right side of the clearance 48. Motion of the carriage in carriage return direction is limited by the margin stop 33 traveling rightwardly into a relation of engagement with the counterstop 46. The motion of the carriage in letter-feed direction is limited by the margin stop 34 riding leftwardly against the counterstop 46 and displacing the latter leftwardly to the limit provided by the clearance 48. When the carriage in the course of typing a line nears the leftward limit, the margin stop 34 during a letter-feed movement engages the counterstop 46 to displace it substantially the equivalent of a letter-feed space. This displacement is utilized to cause the locking of the type keys when a certain line-end position has been reached, in a manner not shown but well known in the art. Subsequently to this, additional characters may be typed after the counterstop is lowered by operation of a margin release key, not shown.

In advance of reaching the counterstop 46, the margin stop 34 may operate a usual bell signal, not shown, as a first warning to the operator of the approach of the line end.

For the moment drawing attention again to the construction of the margin stop detenting device 37, it will be noted that the tooth 42 of the pintle in the margin stop 33 tends to bite firmer into the engaged tooth notch when the margin stop rides against the counterstop. On the other hand the tooth 42 of the pintle in the margin stop 34 tends to bite firmer into the rack notch 36 when margin stop 34 limits carriage travel in cooperation with the counterstop. The notches 36 are of V form, very wide, and afford strong teeth therebetween. Moreover, by reason of the shape of the notches, the teeth 42 of the pintles can likewise be of a very strong form, and also will freely enter the wide notches, and will take a firm grip therein.

Adjustment of either of the margin stops 33 and 34 is effected upon operation of a remote control 66, through movement of the carriage. This is after a margin stop to be adjusted is first located against the counterstop and thereby selected for adjustment. For effecting the release of whichever stop 33 or 34 is selected for adjustment, there is provided forwardly of the counterstop 46 a margin stop releaser in the form of a slide 53 which by an upward displacement is adapted to release the locking device 37 of the selected stop. For releasing action upon said detenting device, said slide 53 has a saddle 54 which is adapted for engagement with a protuberance or pin 55 provided on and projecting forwardly from the pintle arm 41. Said slide 53 is guided and retained near its top for sliding movement in a notch 60 which is generally of dovetail shape. An arm 56 on which the lower end of the slide 53 is pivotally carried by means of a pin 57, serves to guide the slide vertically at

a lower point. Said arm 56 is pivotally carried on a stud 59 provided in a bracket 58 which is carried within the housing 51. A spring 61 having opposite ends attached to the arm 56 and an arm 62 of the bracket 58, urges the slide 53 to the normal, lower position wherein an ear 63 of the arm 56 abuts the bracket 58 as in Figure 3.

The said manipulative control 66 is preferably provided upon the carriage 10, and through a mechanism to be described presently, may operate said releaser or slide 53 in any position of the carriage. Said mechanism comprises a bar 67 extending lengthwise of the carriage, which normally with slight clearance underlies a roll 68 carried by a pin 72 on the slide 53. Said bar 67 is of rectangular cross section for stiffness, and is guided at opposite ends for bodily upward displacement by means of headed studs 70 projecting rigidly from the margin stop supporting bar 32, said bar having at each end an upreaching extension 69 provided with a slot 71 for guided association with one of the studs 70, and each of the studs having a large spacer 69a between its head and the bar 32. A rod 73 extending between the ends 14 of the carriage has near each carriage end an arm 74 which has an articulation as at 75 with the bar 67. The rod 73 is pivotally carried upon the carriage in a manner to be brought out later in detail, and is pivotally displaceable by the manipulative control 66 in order to raise the bar 67 and thereby operate the margin stop releaser 53, the manipulative control 66 being in the form of a lever and having a link connection 76 with an arm 77 reaching rearwardly from the rod 73. For pivotal support of the rod 73, see Figures 5 and 7, each carriage end 14 has a bracket extension 78 secured thereto by a screw 80 and by the screw 85 which fastens the margin stop bar 32. The manipulative control 66, by means of a pivot stud 81, is carried on a further bracket plate 82 which as indicated by a screw 83 is rigid with the bracket 78 on the right carriage end.

As illustrated in Figure 2, the rod 73 carries the arm 77 upon a reduced round end-portion 86, said arm 77 having rigid therewith a long sleeve 87 which has keyed association at 88 with the rod 73. A nut 91 on the rod portion 86 clamps the sleeve 87 with its arm 77 fast on the rod 73. Said sleeve 87 pivots in the right hand end of the carriage in the bracket 78 thereat, and at the left hand end of the carriage the rod 73 pivots directly in the bracket 78 thereat. It will thus be seen that the rod 73, the two arms 74, the sleeve 87 and the arms 77 constitute a unit pivotally carried on the carriage.

According to the invention, as stated hereinbefore, a margin stop to be releasable for adjustment must first be brought into a relation of engagement with the counterstop 46 by carriage movement. To compel such procedure, and eliminate waste manipulations, there is provided in association with the margin stop releaser 53 a blocking element or controller 95. This controller blocks the releaser 53 against upward, margin stop releasing movement at all times except when one or the other margin stop 33, 34 has been moved into margin establishing relation with the counterstop 46. As best seen in Figures 1, 3 and 4, said controller 95 is carried near its lower end seatedly in a circumferential groove of the stud 57 of the stop releaser 53, the controller 95 being provided with a slot 96 of key-hole form to button it to the stud 57, a strong spring 97 stretched between the said stud 57 and the lower extremity of the controller, keeping the lower, reduced end

of the slot 96 permanently drawn up and seated in the underside of the circumferential groove of the stud 57. The controller 95 reaches contiguous to the releaser 53 upwardly above the pin 12 and is perforated to fit loosely a spacing collar between the roller 68 and the releaser 53, and has capacity for some displacement toward the front of the machine. The spring 97, aforementioned, tends to keep the controller 95 resiliently leaning rearwardly against the releaser 53. While the controller is so leaning against the releaser 53, ears 98 rearwardly reaching thereon and flanking the opposite sides of the releaser 53, underlie the top plate 50 of the housing 51. Consequently the releaser 53 is blocked or locked against upward movement if the stated normal condition prevails. Furthermore, the bar 67 by being blocked against upward movement by the roll 68 on the controller 95 in turn blocks operation of the control 66. However, this condition, as will become evident, is prevalent only so long as neither margin stop 33, 34 is in active engagement with the counterstop 46.

The controller 95 embodies on the front side thereof, near its upper end, a V-shaped cam 101 in the form of an attached plate. As either margin stop 33 or 34 is brought into margin establishing relation with the counterstop 46 by movement of the carriage, the beveled rear end of the pin 55 of the detent device for such stop engages the cam 101 and by riding to the crest thereof displaces the controller 95 forwardly about the point of fulcrum afforded by the groove of the pin 57. The displacement is sufficient to position the controller ears 98 clear of the rear edge of the plate 50 so that the releaser 53 is thus free for upward, stop unlocking movement.

From the foregoing it will be seen that operating pressure exerted on the control 66 can have a margin stop releasing effect only in the event a margin stop has previously been brought into a position against the counterstop 46, or consequently to establishment of such position by carriage movement, providing operating force on the control is then still applied. In other words, whether operating pressure on the control 66 is exerted prematurely or not, there will under no circumstances occur a release of a margin stop 33 or 34 until such a stop is in or approximates a margin establishing relation with the counterstop 46. If neither of the stops is in such position, then the controller 95 will remain in rearward position as illustrated in Figure 1, with its ears 98 underneath the plate 50.

When the releaser 53 moves upwardly into engagement with the pin 55 to release the detent device 37 of the stop 33 or 34, then the pin 55 of such stop will be seated in the saddle 54 of the releaser, wherefore so long as the releaser 53 then is maintained operated, the stop is held stationary with respect to the counterstop 46. The stop is then adjustable along the bar 32 through carriage movement, the roll 68 having rolling contact with the bar 67. When subsequently through carriage movement the position of the carriage is reached where the margin stop is desired to be active in the future, the control 66 is released and the bar 67 will restore to the normal position seen in Figure 1, and, furthermore, the releaser 53 will restore, and the 70 detent device 37 will restore to margin stop holding position under the tension of the spring 43, thus securing the stop in the new position as on the bar 32. To assist or assure the restoration of the detent device, the controller has a 75

top ledge 102 overlying the pin 55 of the releaser, the ledge being effective during the restoration of the releaser 53 to descend on the pin 55. The lateral ends of the ledge 102 are slightly upturned to prevent the pins 55 from catching thereon when during carriage movement either margin stop approaches the counterstop 46.

As has been stated the actual adjustment of a margin stop 33 or 34 is preceded by first bringing the stop to be adjusted against the counterstop 46 by carriage movement. However, if an operator exerts operating pressure on the control 66 prematurely, a margin stop will nevertheless become appropriately unlocked when through carriage movement the appropriate relation between the stop and counterstop is established.

For bringing the carriage return margin stop 33 against the counterstop 46 the operator may merely push the carriage rightwardly inasmuch as usual ratcheting action of the escapement permits this. For bringing the line end margin stop against the counterstop, the carriage release lever 24 may be operated. Once a margin stop to be adjusted is in position against the counterstop 46, such stop is adjustable by carriage movement if merely the control 66 is operated, said control being connected operatively with the carriage release lever 24 to free the carriage 10 for movement. Specifically for freeing the carriage, the control 66 has below its pivot stud 81 a link 104 connected thereto which reaches forwardly to a bell crank structure comprising two spaced arms 105, 106, connected by a shaft 107, the latter being pivotally accommodated in the right carriage end 14. The arm 106 has a connecting joint 110 with the lower end of the release lever 24. Whenever the control 66 is capable of operation, said release lever 24 is operated by means of the parts 104 to 106, inclusive, thereby lifting the rack 17 free of the pinion 22 and freeing the carriage for movement to relocate the appropriate margin stop. A pin-and-slot connection 111 between the arm 105 and the link 104 provides that the carriage release lever 24 be operable without effect on the control 66.

Summary

To adjust the line end margin stop 34 the operator best operates the carriage release lever 24 to bring this stop first against the counterstop by carriage movement. The detent device 37 of the margin stop 34 is then in position for operation by the releaser 53 and additionally the controller 95 will have been displaced forwardly by the cam 101 so that the releaser 53 is free for upward movement. During the stated movement of the carriage the operator may exert operating pressure on the control 66 but this is of no avail until the controller 95 is forwardly cammed by the cam 101. Upon operation of the control 66 either by reason of continued pressure thereon or by finger pressure thereon following the movement of the margin stop against the counterstop 46, the bar 67, by operation of the rod 73, will receive an upward movement and will displace the roller 68 with the releaser 53 upwardly. At the same time through the link 104 and the parts 105 to 107, inclusive, the carriage release lever with associated mechanism will become operated. The margin stop 34, in consequence of the foregoing, is then free on the rack bar 32 for adjustment and also is rendered stationary with respect to the counterstop 46, wherefore movement of the carriage will then effect a relocation of the margin stop along

the rack 32, the operator being required to release the control 66 when the position of the carriage has been reached at which it is desired to have the stop located. The release of the manipulative control restores the carriage to the control of the escapement and restores the releaser 53, wherefore the margin stop will become secured in its new location on the bar 32. The releaser being restored, it follows that the margin stop is again free for movement bodily with the carriage and to cooperate with the counterstop 46 in margin gaging action.

The procedure for adjusting the return limiting margin stop 33 is similar to the procedure outlined in connection with the stop 34, except that the margin stop 33 may be brought against the counterstop by merely pushing the carriage rightwardly in return direction, the usual typewriter escapement permitting such movement.

It will be understood that the adjustable stops 33, 34 may be carried on the frame and that the counterstop may be on the carriage, and that many modifications and departures may be resorted to within the general purposes and scope of the invention.

What is claimed is:

1. In a typewriting machine, a frame, a carriage movable lineally on said frame, a margin stop, means to support said margin stop for adjustment in parallel with the movement of the carriage, means to lock the margin stop in adjusted position and in condition for release, a counterstop with which said margin stop assumes an engaged relation in limiting carriage travel in one direction, a device including a manual control, to release the margin stop locking means and to render the margin stop stationary with respect to the counterstop, and governing means including means adjustable along with the stop to cause said device to function effectively upon application of operating force on said manual control only if the margin stop and said counterstop are in or approximate said engaged relation, or consequently to establishment of such relation through carriage movement during maintenance of operating force on said manual control.

2. In a typewriting machine, a frame, a carriage movable lineally on said frame, a margin stop, means to support said margin stop for adjustment in parallel with the movement of the carriage, means to lock the margin stop in adjusted position and in condition for release, a counterstop with which said margin stop assumes an engaged relation in limiting carriage travel in one direction, a device capable of effective operation to release the lock means of said margin stop and to hold the latter stationary with respect to the counterstop, two supplementary control means for said device to cause by combined action an effective operation of said device, one of said control means comprising a manual control element remote to said stop, and the other control means comprising cooperative means on said device and said margin stop to provide for effective operation of the device responsive to application of operating force on said manual control if a relation of engagement of the margin stop with the counterstop exists, or responsive to establishment of such relation under condition of applied operating force on said control element.

3. In a typewriting machine or the like, having a frame, and having a letter-feed carriage movable lineally on the frame; a margin stop,

means to support said margin stop on said carriage adjustably in parallel with the line of movement of the carriage, means to lock said margin stop in different positions of adjustment and in condition for release, a counterstop on the frame with which said margin stop assumes an engaged relation in limiting carriage travel in one direction, a device including a manually operable member in a location remote to said margin stop for releasing said stop locking means and rendering the margin stop stationary with respect to the frame, and means including an element on said margin stop, having control over said device so that if operating force is applied to said member there will result an effective operation of said device only if the margin stop is in or approximates said engaged relation with the counterstop or consequently to establishment of such relation by carriage movement under maintenance of operating force on said member, the margin stop being adjustable to a new position upon effective operation of said device through movement of the carriage.

4. In a typewriting machine, a frame, a carriage movable lineally on said frame, a margin stop, means to support said margin stop for adjustment in parallel with the movement of the carriage, means to lock the margin stop in adjusted position and in condition for release, a counterstop with which said margin stop assumes an engaged relation in limiting carriage travel in one direction, a device including a manual control to release the margin stop locking means and to lock the margin stop stationary with respect to the counterstop, and means to block said device against operation at all times except when the margin stop and the counterstop are in or approximate said engaged relation, said blocking means comprising, a releasable blocking member, and means to release the blocking member under margin stop control whenever said margin stop reaches said engaged relation.

5. In a typewriting machine, a frame, a carriage movable lineally on said frame, a margin stop on said carriage, means to support said margin stop on the carriage for adjustment in parallel with the movement of the carriage, means to lock the margin stop in adjusted position and in condition for release, a counterstop on the frame with which said margin stop assumes an engaged relation in limiting carriage travel in one direction, a device including a manual control to release the margin stop locking means and to hold the margin stop stationary with respect to the counterstop, blocking means, including a member on the frame, normally conditioning said device against operation by said control, and means including means associated with the margin stop for movement therewith parallel to the carriage to render said blocking means automatically ineffective whenever the carriage is given a position so that the margin stop is in or approximates said engaged relation with the counterstop.

6. In a typewriting machine, a frame, a carriage movable lineally on said frame, a left and a right margin stop, means to support said margin stops for adjustment in parallel with the carriage, means for each margin stop to lock it individually in adjusted position and in condition for release, counterstop means with which the two margin stops are adapted to assume opposite carriage-travel-limiting relations, a device including a releaser, operable to release whichever margin stop may be in said carriage-travel-

limiting relation with said counterstop means, and at the same time to hold such margin stop stationary with respect to the counterstop means, means to block said releaser against operation, and means including means on each margin stop to incapacitate said blocking means whenever a margin stop is brought into carriage-travel-limiting relation with the counterstop means.

7. In a typewriting machine or the like, having a frame, and a carriage movable lineally on said frame; a carriage stop, means to support said stop for adjustment in parallel with the movement of the carriage, means to lock said stop in adjusted position and in condition for release, a counterstop with which said stop assumes an engaged relation in limiting carriage travel in one direction, and means to release said stop lock means comprising, a manually operable control remote to said stop, governing means supported for adjustment along with said stop, and means under supplemental control of said manually operable control and said governing means to effect a stop releasing operation, if the stop by carriage movement and under condition of applied operating force on said manually operable control is brought substantially into said engaged relation, or if the stop is substantially in the said engaged relation and then operating force is applied on said manually operable control.

8. In a typewriting machine or the like, a frame, a carriage lineally guided on said frame, a carriage stop, means to support said stop on the carriage for adjustment in parallel with the carriage, a releasable stop lock on said stop, a stop releaser operably supported on the frame and being in the direction of movement of the carriage very small in comparison with the carriage, means on said stop operable by said releaser to release said stop lock whenever the stop occupies a specific position relative to said frame, means to operate said releaser including, a manual control remote to said stop, and governing means comprising means on said carriage supported stop effective if the stop by carriage movement and under condition of applied operating force on said manual control is moved to said specific position, to govern said releaser to give forth a stop releasing operation at the end of such movement.

9. In a typewriting machine or the like, a frame, a carriage movable lineally on said frame, a carriage stop, means to support said stop for adjustment in parallel with the movement of the carriage, means to lock said stop in adjusted position and in condition for release, a counterstop with which said stop assumes an engaged relation in limiting carriage travel in one direction, a releaser operable to release said stop and being in the direction of movement of the carriage very small in comparison with the carriage, means on said stop for operation by said releaser to release said stop lock means whenever said stop approximates said engaged relation with the counterstop, means including a manual control for operating said releaser, and means including governing means for said releaser carried on said stop, effective if the stop by carriage movement and under condition of applied operating force on said manual control is moved into said engaged relation, to control said releaser to give forth a stop releasing operation at the end of such movement.

10. In a typewriting machine or the like, a frame, a carriage movable lineally on said frame,

a carriage stop, means to support said stop for adjustment in parallel with the movement of the carriage, means to lock said stop in adjusted position and in condition for release, a counterstop with which said stop assumes an engaged

5 relationship in limiting carriage travel in one direction, a releaser operable transversely of the carriage to release said stop when said stop approximates said engaged relationship with the counterstop, manually operable means to operate said releaser, means including governing means for said releaser supported for adjustment along with said stop, effective if the stop by carriage movement and under condition of applied operating force on said manually operable means is moved into said engaged relation, to control said releaser to give forth a stop releasing operation at the end of such movement, and means supported for adjustment along with said margin

20 stop and intermeshing with said releaser at stop releasing operation thereof to hold said margin stop stationary with respect to the counterstop.

11. In a typewriting machine or the like having a frame member, and a carriage member movable 25 lineally on said frame member; a stop supported on one of said members for adjustment in parallel with the movement of the carriage member and including means to lock said stop in adjusted position and in condition for release, a counterstop 30 on said other member with which said stop is engageable in the position of the carriage member defined by the adjustable stop, a device adapted for operation to release the locking means for said stop, and means to suppress operation of said 35 releasing device in all positions of the carriage member except the one defined by said stop, said suppressing means comprising governor means including means adjustable along with the stop.

12. In a typewriting machine or the like, a 40 frame, a carriage movable lineally on the frame, a margin stop supported on the carriage for adjustment thereon in parallel with the carriage and including means to lock said margin stop in adjusted position and in condition for release, a counterstop 45 on the frame with which said margin stop is engageable for limiting carriage travel, a stop releaser substantially at the middle of the machine, operable transversely of the carriage to release said stop lock means when said margin 50 stop approximates engaged relation with said counterstop, carriage supported means to operate said stop releaser, comprising a bar on the carriage substantially coextensive therewith and adapted in any position of the carriage to operate 55 said stop releaser, and means to suppress stop lock releasing operation of said bar in all positions of the carriage except one wherein the said margin stop approximates engaged relation with said counterstop, said means comprising governor 60 means adjustable along with the margin stop, and means on said frame cooperative with said governor means.

13. In a typewriting machine or the like, having a frame, a carriage movable lineally on said 65 frame and a releasable letter-feed mechanism; a carriage stop, means to support said stop for adjustment in parallel with the movement of the carriage, means to lock said stop in adjusted position and in condition for release, a counterstop 70 with which said stop assumes an engaged relation in limiting carriage travel in one direction, and means to release said stop lock means comprising, a manually operable control remote to said stop, governing means supported for adjustment along with said stop, and means under supplemental

75

control of said manually operable control and said governing means to release said stop and concomitantly to establish a released condition of said letter-feed mechanism, if the stop by carriage movement and under condition of applied operating force on said manually operable control is brought substantially into said engaged relation, or if the stop is substantially in the said engaged relation, and then operating force is applied on said manually operable control.

14. In a typewriting machine or the like having a frame member, a carriage member movable lineally on said frame member and a releasable letter-feed mechanism; a stop supported on one of said members for adjustment in parallel with the movement of the carriage member and including means to lock said stop in adjusted position and in condition for release, a counterstop on said other member with which said stop is engageable in the position of the carriage member defined by the adjustable stop, a device adapted for operation to release the locking means for said stop and to release at the same time the letter-feed mechanism, and means to suppress operation of said device in all positions of the carriage member except the one defined by said stop, said suppressing means comprising governor means including means adjustable along with the stop.

15. In combination with a typewriter having a frame, an escapement controlled carriage, and means operable for disengaging said carriage from said escapement control; two margin stops slidably mounted on said carriage, a dog for resetting either of said stops along said carriage, a driving unit to drive said operable means and said dog, and a displaceable controlling element in the path of said stops adapted to prevent the transfer of power from said unit to said dog except at such times when the controlling element is displaced by either one of said stops during a resetting operation.

16. In a typewriting machine or the like having a frame member and a carriage member movable lineally on said frame member; a stop supported on one of said members for adjustment in parallel with the movement of the carriage member and including means to lock said stop in adjusted position and in condition for release, a counterstop on said other member with which said stop is engageable in a position of the carriage member defined by the adjustable stop, a manual control on the carriage member, a device positively operable by said manual control in any position of the carriage member to release said locking means for said stop, means to suppress operation of said device in all positions of the carriage member except the one defined by said stop, and means responsive to the operation of said device to hold said stop stationary with respect to said other member, whereby if the carriage member is moved to the position defined by said stop under condition of manual operating force applied on said control, said device and control will become operated automatically, making perceptible to the operator that adjustment of the stop will ensue at further movement of the carriage member.

17. In a typewriting machine or the like having a frame and a carriage movable lineally on said frame; a stop supported for adjustment in parallel with the movement of the carriage and including means to lock said stop in adjusted position and in condition for release, a counterstop with which said stop is engageable in a carriage position defined by the adjustable stop, a

manual control, a device positively operable by said manual control to release said locking means for said stop, means to block operation of said device and therefore said control, arranged for displacement from an effective to an ineffective position, and means adjustable along with said stop and engageable with the blocking means to displace it to ineffective position as the carriage reaches the position defined by the adjustable stop, whereby whenever the carriage is moved to the position defined by said stop under condition of manual operating force applied on said control, said device and control will become operated automatically, making perceptible to the operator that adjustment of the stop will ensue at further carriage movement.

18. In a typewriter in combination, a carriage carrying right and left hand settable marginal stops, a dog to disengage, hold, and re-engage either of said stops in a line along the length of said carriage, a driving unit to actuate said dog, and a governing element displaceable by one or the other of said stops and adapted to time the imparting of force to said dog from said unit by being displaced.

19. In a margin-setting mechanism, a frame, a carriage on said frame, a plurality of margin stops slidably disposed on said carriage, a dog on said frame for resetting either of said stops, a driving unit on said carriage, and a controlling element on said frame normally preventing said unit from driving said dog and adapted to enable said unit to drive said dog upon the impinging of either of said stops against said element by moving said carriage.

20. In a typewriting machine or the like having a frame member and a carriage member movable lineally on the frame member; a margin stop supported on one of said members for adjustment thereon in parallel with the movement of the carriage member and including means to lock said stop in adjusted position and in condition for release, a counterstop on the other member with which said stop is engageable for arrest of the carriage member, a device operable to release said stop and including a part on said frame member, and means to suppress the operation of said part except when the stop is in engagement with the counterstop, comprising, operation blocking means for said part mounted for movement from an effective to an ineffective position, and means to move said blocking means to ineffective position, comprising, a cam element on said stop, and a cam element on the frame member displaceable transversely to the carriage member by said first cam element.

21. The invention set forth in claim 20, said stop movable relatively to the counterstop out of cooperative range therewith, and said cam elements comprising cam faces formed for one cam element to glide over the other in either direction of movement of the carriage member.

22. In a typewriting machine or the like, a frame, a carriage movable lineally on said frame, a carriage stop, means to support said stop for adjustment in parallel with the movement of the carriage, means to lock said stop in adjusted position and in condition for release, a counterstop with which said stop assumes an engaged relation in limiting carriage travel in one direction, and means to release said stop locking means and concomitantly to hold said stop stationary with respect to said counterstop, comprising, a control remote to said stop, and means to trans-
75 late operating force applied on said control into

15

an effective operation of said lock releasing and stop holding means contingent on said stop being in the said position of engagement with the counterstop or contingent on establishment of such engagement by carriage movement while operating force is sustained on said control.

23. In a typewriting machine or the like, a frame, a carriage movable linearly on said frame, a left and a right margin stop, means to support said stops for individual adjustment in parallel with the carriage, means to lock said stops individually in adjusted position and in condition for individual release, counterstop means with which the two margin stops are adapted to assume opposite carriage-travel-limiting relations, and means to release the locking means with respect to either of said stops, said last means including, a manual control remote to both said stops and separate operation governing means for said releasing means, adjustable along with each of the stops to cause translation of operating force applied on said control into an effective op-

eration of the releasing means contingent on and with reference to whichever stop may be residing in carriage-travel-limiting engagement with the counterstop means, and also to cause translation of applied operating force on said control into an effective operation of the releasing means with reference to whichever stop by carriage movement and under condition of applied operating force on said control is brought into engaged relation with the counterstop means.

HARRY C. YAEGER.
